UNITED STATES PATENT OFFICE.

EDWIN O. BARSTOW, OF MIDLAND, MICHIGAN, ASSIGNOR TO THE DOW CHEMICAL COMPANY, OF MIDLAND, MICHIGAN, A CORPORATION OF MICHIGAN.

METHOD OF MAKING LEAD ARSENATE.

1,349,707.

Specification of Letters Patent. Patented Aug. 17, 1920.

Application filed June 28, 1918. Serial No. 242,336.

To all whom it may concern:

Be it known that I, EDWIN O. BARSTOW, a citizen of the United States, and a resident of Midland, county of Midland, and State of Michigan, have invented a new and useful Improvement in Methods of Making Lead Arsenate, of which the following is a specification, the principle of the invention being herein explained and the best mode in which

10 I have contemplated applying that principle, so as to distinguish it from other inventions.

It is known that arsenic acid will precipitate as an arsenate the lead contained in the sub-acetate or basic lead acetate. The object of the present invention is to provide a process for the utilization of this reaction in the manufacture of lead arsenate on a commercial scale. A further object is to provide a continuous process, that is one in which the several materials utilized may be supplied continuously at proper stages in the process and the desired lead arsenate withdrawn at the end. The advantage of such a process over those currently in use, in which arsenate is made up in batches, will be obvious.

To the accomplishment of the foregoing and related ends the invention then consists of the steps hereinafter fully described and particularly pointed out in the claims, the following description and the annexed drawing setting forth in detail certain steps embodying the invention, such described steps constituting, however, but one of various ways in which the principle of the invention may be used.

In said annexed drawing:—

Figure 1 is a diagrammatic representation of an apparatus arranged for carrying out my present improved process; and Fig. 2 is a diagrammatic representation of the several steps involved in such process.

Referring more especially to the apparatus as outlined in Fig. 1, the first step of the process consists in continuously mixing together in a suitable reaction chamber 1 lead oxid and lead acetate solution, the former being present in chemical excess of the latter. The lead oxid is continuously supplied from an outside source while the lead acetate solution is returned to the stage in question from a subsequent step in the process as will be presently described. These two ingredients are preferably supplied to

the bottom of the chamber 1 where suitable stirring means 2 serves to thoroughly intermix the same, and as the level of the liquid in the chamber rises, such liquid will overflow into a second reaction chamber 3 likewise supplied with suitable stirring means 4. The solution thus overflowing into chamber 3 contains principally basic lead acetate in solution and arsenic acid is here supplied to such solution from an outside source, the result being the formation of a precipitate of lead arsenate, leaving a solution of lead acetate and free acetic acid.

The mixture of lead acetate and free acetic acid solution with precipitated lead arsenate is conducted from chamber 3 to a suitable settling tank 5 from the upper portion of which such solution, practically clear, is withdrawn and pumped back to chamber 1, thus supplying the lead acetate solution there needed. The lead arsenate which settles as a sludge in the bottom of chamber 5, is pumped to a mixing box 6, where it is mixed with water, and then overflowing into a second settling tank 7, is again separated out as a sludge and finally pumped to a filter 8. The overflowing liquor from tank 7 joins the solution withdrawn from the upper portion of tank 5, and with the latter is conducted to reaction chamber 1. The arsenate is finally separated out in the filter and may thereafter be dried or utilized in paste form, as desired.

It will be understood that any number of mixing boxes and settling chambers may be utilized in washing the lead arsenate after its separation from the solution in settling tank 5, instead of the single such mixing box and chamber illustrated; also that instead of having a single reaction chamber 3, the reaction between the arsenic acid and basic lead acetate solution may be continued through two or more similar chambers. It may also be found desirable to concentrate the basic lead acetate solution which overflows from reaction chamber 1, depending upon its degree of dilution. Suitable evaporating means may accordingly be interposed between said reaction chamber and chamber 3, in which the arsenic acid is added to such basic lead acetate solution.

By the succession of steps just described, including the continuous return of the lead acetate and acetic acid solution from the sec-

ond step to the first, the addition of lead acetate from an extraneous source is unnecessary except in starting the process and in making up the small waste that may occur.

- 5 **Moreover, by maintaining the lead oxid in excess in the first reaction chamber the only regulation that is necessary is in connection with the supply of arsenic acid, which should be somewhat less than sufficient to completely react with the lead acetate. The process accordingly not only is a continuous one but also largely automatic, requiring a minimum amount of attention and care in operation.**
- 10 **The several steps of the process are clearly indicated in Fig. 2, the reactions that are involved being represented by the following equations:**

25 It will be noted that the foregoing equations are based on the assumption that the simplest basic salt ($PbOH.C_2H_3O_2$) is formed as a result of the second reaction, and that the arsenate produced is the orthoarsenate, $Pb_3(AsO_4)_2$. The commercial product, however, may contain other arsenates, just as other basic acetates may be formed by the first reaction, without affecting the character or success of the process.

30 Other modes of applying the principle of my invention may be employed instead of the one explained, change being made as regards the method herein disclosed, provided 40 the step or steps stated by any of the following claims or the equivalent of such step or steps be employed.

I therefore particularly point out and claim as my invention:—

1. In a method of making lead arsenate, 45 the steps which consist in maintaining a mixture of lead oxid and lead acetate, the former being present in excess; continuously separating out the basic lead acetate thus formed; and continuously mixing such basic 50 lead acetate solution with arsenic acid, whereby lead arsenate is precipitated.

2. In a method of making lead arsenate, the steps which consist in maintaining a mixture of lead oxid and lead acetate, the former being present in excess; continuously separating out the basic lead acetate thus formed; continuously mixing such basic lead acetate solution with arsenic acid, whereby lead arsenate is precipitated, leaving free 60 acetic acid; and continuously separating and returning such acetic acid to the first step to react with lead oxid there and form more lead acetate.

3. In a method of making lead arsenate, 65 the steps which consist in continuously mixing lead oxid and lead acetate solution containing free acetic acid in a suitable reaction chamber; continuously drawing off from such chamber the solution of basic lead acetate that is thus formed; continuously mixing in a separate reaction chamber such basic lead acetate solution with arsenic acid, whereby lead arsenate is precipitated, leaving lead acetate with free acetic acid; passing the resulting mixture through a settling chamber; continuously withdrawing such lead arsenate from the bottom of such settling chamber; and continuously withdrawing such acetic acid from the top of such settling chamber and returning the same to the 70 first reaction chamber.

Signed by me, this 20th day of June 1918.
 EDWIN O. BARSTOW.
